C. T. GROSJEAN.

SPOON HANDLE.

Patented Mar. 9, 1886.

No. 16,561.

UNITED STATES PATENT OFFICE.

CHARLES T. GROSJEAN, OF NEW YORK, N. Y., ASSIGNOR TO TIFFANY & CO.
OF SAME PLACE.

DESIGN FOR A SPOON-HANDLE.

SPECIFICATION forming part of Design No. 16,561, dated March 9, 1886.

Application filed January 15, 1886. Serial No. 188,693. Term of patent 14 years.

To all whom it may concern:

Be it known that I, CHARLES T. GROSJEAN, a citizen of the United States, and a resident of the city, county, and State of New York, have invented a new and original Design for Spoon-Handles, of which the following is a specification, reference being had to the accompanying drawings, forming part thereof.

This design consists in a paddle-shaped head with a massive raised molding, which incloses the shape of the handle, together with a fine-line molding on the inner side of such molding. At the head, on front and back, there is a shell-like ornament, in which these moldings terminate on each side of the spoon. On the front, where the handle reaches the bowl, there is a shell ornament in leaf-like form. On the back, where the handle expands into the bowl, there is a raised or fluted fan, beginning with the raised swell at the upper part, then falling into long gadroons, which expand into the fan-like form above mentioned. There is left below the shell-like ornament, on both front and back, a clear space, upon which may be placed a monogram or coat of arms, one upon the front and the other upon the back, as seen in the drawings.

In the drawings, Figure 1 is a front view of a spoon containing my design. Fig. 2 is a rear view thereof.

a is the massive raised molding inclosing the shape of the handle on both front and back.

b is the fine-line molding running on the inner side of the large molding.

c is the shell-like ornament at the top of the spoon, in which the large and small moldings terminate, thus breaking said moldings into two parts.

d is the shell ornament of leaf form, at which the said moldings terminate at the lower end of the handle on the front.

e is the raised swell or fluted upper por-

tion, and *f* is the fluted lower portion, of the fan-like ornament, the long gadroons *g* of such lower part extending out into and covering a considerable portion of the upper part of the bowl of the spoon.

h is a coat of arms, which may be placed on the front of the spoon below the shell-like ornament.

i is a monogram, which may be placed on the back in about the same location as the coat of arms on the front.

This design of handle also may be placed on the handle of a fork.

I claim—

1. In a design for a spoon-handle, a paddle-shaped head containing a massive raised molding, *a*, with a fine-line molding, *b*, on the inner side thereof, with a shell-like ornament, *c*, at top, in which said moldings terminate on opposite sides, substantially as shown.

2. In a design for a spoon-handle, a paddle-shaped head containing a massive raised molding, *a*, with a fine-line molding, *b*, on the inner side thereof, a shell-like ornament, *c*, at top, in which said moldings terminate on opposite sides, together with a shell ornament of leaf-like form, *d*, into which the said moldings extend at base of handle, substantially as shown.

3. In a design for a spoon-handle, a paddle-shaped head containing a massive raised molding, *a*, with a fine-line molding, *b*, on the inner side thereof, a shell-like ornament, *c*, at top, in which said moldings terminate on opposite sides, together with a raised or fluted fan-like ornament consisting of a raised swell or fluted upper portion, *e*, and long gadroons *g*, ⁷ extending out therefrom and expanding into fan-like form, *f*, substantially as shown.

CHARLES T. GROSJEAN.
